UNITED STATES PATENT OFFICE.

HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

MULTIPLE-SWITCH STARTER.

No. 913,999.

Specification of Letters Patent.

Patented March 2, 1909.

Application filed May 20, 1907, Serial No. 374,728. Renewed January 11, 1909. Serial No. 471,775.

To all whom it may concern:

Be it known that I, HENRY J. WIEGAND, a citizen of the United States, residing at Milwaukee, in the county of Milwaukee and State of Wisconsin, have invented new and useful Improvements in Multiple-Switch Starters, of which the following is a full, clear, concise, and exact description, reference being had to the accompanying drawings, forming a part of this specification.

My invention relates to improvements in motor controllers.

It is particularly applicable to controllers in which a plurality of hand operated switches are used for controlling a resistance.

One of the objects of my invention is to provide a means whereby the motor circuit will be opened unless all of the switches are closed, and all of the resistance is removed from circuit.

According to the preferred form of my invention, I provide a plurality of hand operated switches preferably adapted to be closed in a definite sequence for controlling the starting resistance. These switches are retained in their closed position by a low voltage device, and one of the switches is adapted to control the motor circuit. In order that the operator may not leave part of the starting resistance in circuit, I provide a switch for controlling the operating circuit of said low voltage device, which has a tendency to move to a position to render said low voltage device inoperative, and which, during the closing operation of the switches must be held by the operator in a position to render said low voltage device operative. For retaining this switch in a position to maintain the low voltage device operative after all of the switches are closed, I provide a latch which is operated upon the closing of the last switch to mechanically hold the low voltage device switch in a position to render said low voltage device operative.

While I illustrate and describe the preferred embodiment of my invention, which I have worked out for practical application, it will be understood that my invention is susceptible to various modifications and changes.

For the purpose of disclosing my invention, I have illustrated in the accompanying drawings, one form which my invention may take.

In said drawings: Figure 1 is a front elevation of the starting device of my invention, Fig. 2 is a side elevation thereof, Fig. 3 is a detailed view of the latch mechanism for holding the switch in a closed position, Fig. 4 is a sectional top view of one of the switches, and a top view of the cooperating rocking dogs, Fig. 5 is a detailed view of one of the rocking dogs, and Fig. 6 is a diagrammatic view of the circuit connections.

In the embodiment of my invention illustrated, I provide a plurality of switch levers or arms 1, 1^a, 1^b, and 1^c, which are suitably pivoted or journaled at one end, and provided at the opposite end with suitable operating handles. I have shown the several switch levers as journaled upon a shaft or rod 2, which is mounted in bearings 3, formed on brackets 4. The brackets 4 also support a rod 5, which is threaded through a rubber tube 6 that serves as a cushion or buffer against which the extended ends of the switch or levers are adapted to impinge when thrown open. Each of the levers carries a contact device 7 adapted to engage contact surfaces to complete the circuit. Upon the base board 8, upon which are mounted the various operating parts of the device and which may be formed of slate, soapstone or like material, is mounted a contact bar 9 with which one end of the contact device 7 of each arm or lever is adapted to engage, the other end of said device being adapted to engage one of the contact terminals 10, 10^a, 10^b and 10^c, also mounted upon the base 8. The terminal 10 is provided with a binding post 11, by which suitable electrical connections may be made and the terminal 10^c is provided with a binding post 12. Upon the terminal 10 is mounted a carbon block 13 and a similar block 14 is mounted upon the end of the contact bar 9. The switch arm 1 carries laterally extending spring arms 15 and 16, which support upon the ends thereof, carbon blocks 17 and 18 respectively, and which are adapted when the switch arm 1 is moved, to close the circuit, to engage the blocks 13 and 14, whereby the circuit is closed from the terminal 10 to the terminal 9. The further movement of the switch arm 1 causes the contact device 7 thereof to directly connect the terminals 10 and 9. Likewise when the switch arm 1 is moved outward, the contact device 7 leaves

the terminals 10 and 9 before the carbon blocks separate so that any arc formed by the opening of the circuit will take place between the carbon blocks, instead of between 5 metallic surfaces.

Near the upper end of the switch arm is formed a lug 19 which is provided with a laterally extending rod 20 which may take the form of a screw. Mounted upon the base 10 board 8, above the arm 1 is a retaining magnet 21 having an armature 22 pivoted at 23. The armature carries a laterally and upwardly extending lug 24, and when the arm 1 is moved to close the circuit, the rod or projection 15 20 engages the side of the armature 22, to move the same against the magnet pole, and the magnetism of the magnet 21 retains the armature 22 in this position. The swinging of the armature 22 carries the lug 24 upon the exterior of the projection 20, so that the projection will rest in the slot formed between the lug and the armature, and as long as the magnet 21 remains energized, the arm will thus be held in a closed position. When, 25 however, the magnet 21 is deenergized the armature 22 will be released and the weight of the arm 1 will carry the same into position, shown in Fig. 2.

Mounted upon a rod or shaft 25, supported 30 in suitable bearings upon the base plate 8, are rocking dogs 26, 26^a, and 26^b. Each of the dogs has its rear end so shaped as to engage the base plate 8, and limit the downward movement of the dog when free. Upon 35 the end of the dog, to the right hand side, an upwardly extending lip 27 is formed which has its front edge curved and its rear edge perpendicular to the upper surface of the dog. The under side of the dog has a lip 28, 40 extending throughout its entire length, which is rounded off at the left hand edge. The levers 1^a to 1^c are each provided with a latch 29, pivoted to the arm at 30, and set in a slot 31, formed in the arm, the walls of 45 which slot limit the vertical movement of the latch relatively to the arm. Below the latch and formed integrally with the lever is a lug 32, projecting outward toward the base plate and consisting of two parts 33 and 24. 50 The part 33 is square in section and flat upon the end, and when the lever is in a position to close the circuit presents a vertical surface. The upper part of the part 34 is inclined or chamfered at an acute angle. 55 Mounted in the bearings 35, formed in the brackets 4, is a rod or shaft 36, which at one end carries a downwardly and laterally projecting arm 37, and at its opposite end immediately beneath the lever 1^c carries a cross 60 arm 38. One end of the arm is provided with a roller 39 adapted to be pressed into engagement with the projecting end of the lever 1^c, by a coiled spring 40 interposed between the opposite end of the arm and a stud 65 or projection 41 extending from the base 8.

At the lower left hand end of the base 8, a switch arm 42 is pivotally mounted and is held in its open or normal position by a coiled spring 43, mounted upon the pivot stud of the switch. This switch is adapted 70 to make contact with the contact stud 44, and when moved into engagement with the contact 44 will be held in that position by the arm 37, engaging over a pin or projection 45 on the arm 42, when the arm 37 is moved inwardly by the closing of the switch 1^c. When the switch 1^c is thrown closed, the extension thereof moves the end carrying the roller 39 of the arm 38 outwardly, thereby rotating the shaft and throwing the arm 37 inwardly 75 in a position to engage the pin 45 and hold the switch against the tension of the spring 43.

The circuit connections for my invention as applied to a starting rheostat for motors are illustrated in Fig. 6. Referring to this figure the contact terminal 10 is connected with the positive side 46 of the supply main, and the terminal 10^a is connected by the conductor 47, through the armature 48 of the motor, with the negative side 49 of the 80 supply main. The switch arm 42 is connected by a conductor 50 with the negative side 49 of the supply main, and the contact 44 of said switch is connected by conductor 51, through the resistance 52, with one 85 terminal of the magnet 21. The opposite terminal of the magnet is connected by a conductor 52^a with one terminal of the field winding 53 of the motor, the opposite terminal of which is connected to the negative side 49 of the supply main. A branch conductor 54 also connects one terminal of the winding 21 with the contact bar 9. A section of resistance 55 extends between the contact bar 9 and the contact terminal 10^a, 100 and a second resistance 56 is connected between the terminals 10^a and 10^b and is divided into sections and connected also with the terminal 10^b.

The operation of the device above described is as follows: Assuming that it be desired to start the motor, the operator with one hand moves the switch 42 until it engages the contact 44. With his other hand the operator closes the first switch 1. Circuit is then established from the positive side 46 to contact 10, across the switch 1, by conductor 54, through the winding 21, through the resistance 52, by conductor 51, across the switch 42, and by conductor 50, 110 to the negative side of the supply main. This energizes the magnet 21, and when the armature 22 of the magnet is moved into engagement with the pole piece thereof, it is held in that position, thereby holding the 115 arm 1 closed. The closing of the switch 1 also closes the circuit from the positive side to the contact terminal 10, thence across the arm 1, to the contact terminal 9, through the resistances 55 and 56, to contact terminal 120 125 130

10°, thence by conductor 47, through the armature 48 of the motor, and back to the negative side 49 of the line. Circuit is also established from the contact 9, by conductors 54 and 52^a, through the shunt field winding 53. The motor is thus started with all the armature resistance in circuit. In moving the arm 1 to the closed position, the oblique wall 34 of the lug 32 thereof engages 10 under the face of the first rocking dog 26, and moves the same to the position indicated in full lines in Fig. 3. The second switch arm 1^a is now closed, and as the dog 26 is in its raised position, the latch 29 of the arm 15 1^a will ride over the lip 27 of the dog 26, and engage the vertical wall thereof, holding the switch arm 1^a in a closed position. The closing of the switch 1^a cuts out one section 20 55 of the armature resistance. As the second arm 1^a is closed, the inclined wall 34 of the lug 32 of this arm will engage under the face of the second rocking dog 26^a, and raise this dog into its engaging position, where the lip 27 thereof will be engaged by 25 the latch 29 of the arm 1^b. The arms may be thus successively closed until all of the starting resistance is removed from circuit. During the closing operation, the switch 42 must be held closed by the operator against 30 the tendency of the spring 43, in order that the circuit through the magnet 21 will be maintained closed. As the last switch 1^c is closed, the arm 37 is moved inwardly until the end thereof lies in the path of the pin 45 35 and prevents the arm from moving under the influence of the spring 43 to an open position. The magnet 21 is thus maintained operative until it is desired to open the circuit and stop the motor or until the current 40 in the line falls below a predetermined point.

If it is desired to cut in the resistance and open the circuit through the motor, the retaining magnet 21 is deenergized in any desired manner, and the arm 1 will be released and fly outward. In moving outward, the arm 1 permits the first rocking dog 26 to fall and the latch of the switch 1^a is released. The moving of the second switch arm to its open position releases the latch 26^a and permits the third switch arm to open, and in a similar manner each switch arm releases the next succeeding arm until all of the switch arms have been released.

Any attempt to close one of the switch 55 arms out of its regular order will be prevented, due to the fact that the flat face 33 will engage the end of the rocking dog when in a lower position, and it is only when the dog has been raised to the upward position that 60 the flat face 33 is permitted to pass beneath the end of the rocking dog. Moreover unless the rocking dog is in the upper position the latch 29 will not engage the lip 27, and the rocking dog will be held in the upward position only when the preceding switch 65

arm has been closed. The accidental or intentional closing of one of the switch arms out of its regular order is thus prevented.

It may happen that the operator after closing some of the switch arms and before 70 he closes the last arm is called away from the starting device or through ignorance or carelessness leaves the starting device without having closed the last switch arm. As soon, however, as he releases the switch 42 the 75 switch under the influence of the spring 43 will fly open, thereby opening the circuit through the retaining magnet 21, and permitting all of the arms to open and open the circuit through the motor. It will therefore 80 be seen that it is impossible for a careless or ignorant operator to leave a portion of the starting resistance in circuit. The resistance of a starting device is usually constructed of wire which, while sufficiently heavy to 85 carry the current for a short period of time while the motor is being started, is not usually of sufficient capacity to carry current for a considerable period of time. As the operator can not leave the starting device 90 without having closed the last switch, if he remains and holds the hand switch 42 closed and does not close all of the switches, he will immediately be notified of the fact by the heating of the resistance. It is therefore 95 seen that it is impossible for the operator to leave the resistance of the starting device in circuit for any great period of time.

Having thus described my invention what I claim as new and desire to secure by Letters Patent is:

1. The combination with a plurality of switches, of retaining means for holding all of said switches in closed position, manually operated means independent of said switches 105 for rendering said retaining means operative until a certain switch is closed, and means operated by said switch for holding said manually operated means.

2. The combination with a plurality of 110 switches, of retaining means for holding all of said switches closed, means independent of said switches which must be manually held during the closing operation for rendering said retaining means operative, and 115 means operated upon the closing of the last switch for holding said manually held means.

3. The combination with a plurality of 120 switches, of a retaining magnet for holding said switches in a closed position, manually operated means which must be held during the closing operation for rendering said magnet operative, and means operated upon the closing of the last switch for holding said 125 manually operated means.

4. The combination with a plurality of 130 switches, of a retaining magnet for holding said switches closed, a switch which must be manually held during the closing operation

for rendering said magnet operative, and means operated upon the closing of the last switch for holding said manually operated switch.

5. The combination with a plurality of switches, of a retaining magnet for holding said switches closed, a switch manually held during the closing operation for rendering said magnet operative, and automatically held 10 after the closing operation is completed.

6. The combination with a plurality of switches, of a retaining magnet for holding said switches closed, a switch which must be manually held in operative position during 15 the closing operation, and means operated by the last switch for holding said manually operated switch.

7. The combination with a plurality of switches, of a retaining magnet for holding 20 said switches closed, a switch which must be manually held during the closing operation for rendering said magnet operative, and a latch for holding said switch when the last switch of the sequence is closed.

8. The combination with a plurality of switches, of a retaining magnet for holding said switches closed, a switch which must be manually held during the closing operation, and a latch operated by the last switch for 25 holding said manual switch.

9. In a motor controller the combination with a resistance, of a plurality of switches for controlling said resistance, a switch among said switches for controlling the motor 30 circuit, a low voltage device coöperating with said last mentioned switch whereby the same is operated to open the motor circuit in event the voltage falls below a predeter-

mined point, a switch operatively connected with said low voltage device having a tendency to move to a position to cause said low voltage device to cause the circuit to be opened and adapted to be held by the operator against moving to said position during the closing operation of the switches, and a 45 latch operated upon the closing of the last switch of the series for holding said switch in a position to render said low voltage device operative.

10. In a motor controller the combination with a resistance, of a plurality of switches for controlling said resistance, a switch among said switches for controlling the motor circuit, a low voltage device coöperating with said last mentioned switch whereby the 50 same is operated to open the motor circuit in event the voltage falls below a predetermined point, a switch operatively connected with said low voltage device having a tendency to move to a position to cause said low voltage device to cause the circuit to be opened and adapted to be held by the operator during the closing of the first mentioned switches against moving to said position, and a latch operated by the last switch 55 for holding said low voltage device switch against moving to a position to cause said low voltage device to cause the circuit to be opened.

In witness whereof, I have hereunto subscribed my name in the presence of two witnesses.

HENRY J. WIEGAND.
